UNITED STATES PATENT OFFICE.

ANDREW PARVIAINEN, OF CROMWELL, MINNESOTA.

HOT-AIR FURNACE.

Application filed May 22, 1922. Serial No. 562,932.

To all whom it may concern:

Be it known that I, ANDREW PARVIAINEN, a citizen of the United States, residing at Cromwell, in the county of Carlton and 5 State of Minnesota, have invented certain new and useful Improvements in a Hot-Air Furnace; and I do declare the following to be a full, clear, and exact description of the invention, such as will enable others skilled 10 in the art to which it appertains to make and use the same.

This invention relates to an improved hot air furnace, and it has for its principal object to generally improve upon heating devices of this class by providing one of comparative simplicity and durability which is practical and embodies novel means for securing a uniform distribution of the heated air within the outer casing, this means being 20 a chamber in which heat absorbing elements are positioned for retaining and effectively radiating the heat against the wall of the chamber with which the air contacts to become heated.

25 Other objects and advantages of the invention will be apparent during the course of the following description.

In the accompanying drawings forming a part of this application and in which like numerals are employed to designate like parts throughout the same:

Figure 1 is a front elevation of a furnace constructed in accordance with this invention.

35 Figure 2 is a central vertical section thereof.

Figure 3 is a section taken at right angles to Figure 2 on the line 3—3 of Figure 2.

Figure 4 is a horizontal section taken on 40 the lines 4—4 respectively of Figures 2 and 3.

In the drawings, the numeral 1 represents a metal casing having cold air intake openings 2 at its bottom and hot air outlet openings 3 at its top. It may be mentioned here that this furnace is of the portable type and is designed especially for burning wood. However, it is adaptable for use for coal burning too and may be installed in the cellar, and when so installed, the usual hot air conveying pipes will be connected to the discharge openings 3. The casing is equipped on its rear side with a vertical smoke pipe 4 having a suitable damper or valve 5 arranged therein. The casing is further equipped with a plurality of doors at its front or permit access to be had to the interior of the casing for inserting fuel, removing ashes or for other purposes which will be made apparent as the description 60 goes on. It may be conveniently stated here that a passage 6 for the smoke and heated particles carried therewith is arranged at the center of the bottom of the casing and this passage connects at its rear end with the 65 aforesaid smoke pipe and terminates short of the front side of the casing to permit the smoke to enter. Although it is not essential, a longitudinal partition 7 is arranged in and divides the passage in the manner 70 shown. It may also be conveniently set forth here that in practice, the casing will be constructed in any desirable manner and will be of any suitable shape and design.

As before briefly indicated, novel means 75 is arranged inside of the casing for effectively heating the circulating air, this means being such that it insures effective heating of the air even when the fire becomes low. The means in its preferred form comprises 80 a compartment 8 the wall 9 of which is corrugated and is spaced from the walls of the aforesaid casing to provide an air circulating space 10. Arranged within this compartment 8 is a fire box 11 which is supported in spaced relation from the bottom of the casing on the aforesaid passage 6. This fire box is open at its top and a plurality of bars 12 extend transversely across this end and rest on the side walls to provide a grate. 90 As shown, stones or the like 13 are adapted to be packed in the compartment 8 and these stones are to be such as to effectively absorb and retain the heat, the same being heated to a high degree by the smoke which is compelled to pass upwardly through the aforesaid grate and between the packed stones. 95 To insure effective and uniform distribution of the smoke within this compartment 8, I employ divergent baffle plates 14, these being associated with the upper end of the fire box and having their upper edges terminating adjacent the wall of the compartment to provide a limited passage for the smoke 100 between this wall and baffle. I am led to state here that these baffles and aforesaid wall 9 are held together at the proper spaced relation by a plurality of stay bolts 15. Although it is not essential, corrugated plates 16 are placed within the compartment and 110 rest against the fire box with the baffles, these plates serving to act in conjunction with the

stones for absorbing and radiating heat against the wall of the compartment so that the air will be evenly distributed in this compartment and will be caused to contact the entire surface of the compartment to insure a thorough heating of the air.

In the operation it will be seen that the flames from the fire box 11 will impinge upon the stones 13 resting on the grate bars 12 and will in conjunction with the escaping smoke, thoroughly heat these stones. Since they are of a quality to absorb the heat, it will be seen that the heat will be gradually radiated from them to heat the wall of the compartment 8 to a high degree. Hence, the air which enters the aforesaid casing 1 through the openings 2 will contact the surface of this compartment and will become highly heated before it escapes through the discharge openings 3. Hence, a highly desirable and practical portable furnace is thus provided. It is to be emphasized that with the particular construction of furnace described, a considerable amount of fuel will be saved and practical experience with a furnace constructed in accordance with this invention has disclosed the fact that even after the fire has been completely extinguished, the heat retaining elements will serve to keep the wall of the compartment heated for quite some period of time. Thus, even when the fire is out the furnace will function to heat the air which circulates through it. It is evident that a furnace of this type will be highly desirable in that it will not require keeping of the fire over night, yet it will automatically function to keep the house comfortable. Attention is also directed to the fact that with the particular arrangement shown, the escaping particles of combustion and smoke are compelled to pass upwardly through the heat absorbing elements over the grate, downwardly through the restricted passages formed by the baffles, and around the firebox in order to enter the discharge conduit. Consequently, intense heating of the inner casing or compartment is assured.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the

invention. However, I wish it to be understood that minor changes coming within the scope of the invention as claimed may be resorted to if desired.

I claim:

1. A hot air furnace comprising inner and outer spaced casings between which cool air is adapted to pass to be heated, a smoke discharge conduit extending through said inner casing, a fire box arranged in said last named casing, being supported on the conduit, a grate supported on the upper open side of said box, and heat absorbing and radiating elements arranged in said inner casing and partially surrounding the fire box conduit, whereby to compel the smoke and products of combustion to follow a tortuous passage around the fire box before entering the discharge conduit.

2. A hot air furnace comprising a casing, a smoke pipe, a passage for the smoke communicating with said pipe and extending across the bottom of said casing and terminating in spaced relation from one of the walls thereof, a compartment arranged in said casing and having its wall spaced from the walls of said casing to provide a space for the circulation of air, a plurality of heat absorbing and radiating elements positioned in said compartment, the latter communicating with said smoke passage, and a firebox resting on said passage and having an upper open end with a grate positioned thereon to permit passage of the smoke between said heat absorbing elements.

3. A hot air furnace comprising a casing having a smoke pipe and a passage connected to said smoke pipe and extending across the inner face of the bottom of said casing and terminating in spaced relation from one of the walls thereof, a compartment arranged inside of said casing and covering said smoke passage, the wall of said compartment being spaced from the walls of said casing to provide a space for circulation of heated air, heat absorbing elements in the compartment, a fire-box supported on said passage and having its upper open end covered by a grate through the bars of which the smoke is adapted to pass for heating said elements, and baffle plates associated with said fire-box and arranged in said compartment for creating a uniform distribution of the smoke through said elements.

In testimony whereof I have hereunto set my hand.

ANDREW PARVIAINEN.
